BOBBIN CASE RETAINER

Filed March 29, 1930

Fig. 1.

UNITED STATES PATENT OFFICE

JOHN C. DOBYNE, OF ST. LOUIS, MISSOURI

BOBBIN-CASE RETAINER

Application filed March 29, 1930. Serial No. 439,927.

This invention pertains to shoe sewing machines and more particularly to bobbin-case retainers for such machines.

One of the objects of this invention is to provide improved means for releasing the bobbin-case for removal in order to replace an empty bobbin by a full one.

Another object is to provide means whereby the time consumed in changing bobbins may be reduced to a minimum.

Another object is to provide a bobbin-case retainer which may be accurately adjusted to its operating position and which may be released to free the bobbin-case and returned to operating position without deranging such adjustment.

Further objects will appear from the following description taken in connection with the accompanying drawings, in which:

Figure 1 is a plan view showing the shuttle head of a shoe sewing machine and adjacent parts, equipped with a bobbin-case retainer embodying this invention;

Figure 2 is a front view of Figure 1.

Referring to the drawings, 1 designates the shuttle head of a sewing machine in which is mounted for appropriate movement a shuttle carrying a bobbin-case 2 in the usual manner. A retainer or guide arm 3 provided with a stop-bearing 4 is adapted to engage a cooperating stop 5 on the bobbin-case 2 so as to retain the latter in place and to allow for its movement while permitting passage of the thread between the two.

The retainer 3 is pivoted on a vertical pin 6 mounted in the head 1. This pivotal mounting permits the retainer to swing outwardly to the position shown in dotted lines in Figure 1, so as to free the bobbin-case which may then be removed and refilled. The retainer 3 has mounted therein an adjusting screw 7 whose tip engages the head 1 as illustrated in Figure 1. This screw serves as a stop to limit the movement of the retainer 3 in one direction and to adjust its spacing from the member 5. A lock nut 8 may be provided to secure the screw 7 in adjusted position.

The retainer is provided with an extension 9 in which is mounted an adjusting screw 10 provided with a lock nut 11 for securing it

in adjusted position. Pivoted at 12 in a part 13 of the frame of the sewing machine adjacent the head 1, and so as to move transversely of the movement of the retainer 3, is a latch member 14 provided with a handle 15. The latch 14 in one of its positions on the pivot 12 is positioned to be engaged by the tip of the screw 10 which thus provides a stop to prevent the outward movement of the retainer 3 and retain the latter in position before the bobbin-case. In this position the latch 14 rests against a vertical face of the frame 13 so that it is supported against the pressure of the guard.

The latch 14 thus provides an abutment for the screw 10 which may be moved out of engagement with said screw in order to permit movement of the retainer so as to free the bobbin-case. The latch 14 also performs the function of positioning the retainer relative to the frame which when in retaining position holds the retainer in its closed position before the bobbin-case and which may be removed from between the frame and the retainer in order to allow the retainer to be moved to open position.

The extension 9 of the retainer may be equipped with a rearwardly extending pin 16 to whose outer end is connected a spring 17 which is also connected to the frame 13 in such a manner as to urge the retainer 3 outwardly to its open position as indicated by the dotted lines in Figure 1.

In the use of this device, the screws 7 and 10 are adjusted so as to accurately fix the position of the retainer 3 in its closed position. It will be noted that these adjusting screws act in opposition to one another; that is, one of them limits the movement of the retainer in one direction while the other limits its movement in the opposite direction. Accordingly, the retainer may be accurately positioned in its closed position by proper adjustment of these screws. When it is desired to change bobbins the operator simply lifts the handle 15. This raises the latch 14 on its pivot 12 to the position shown in dotted lines in Fig. 2. This movement carries the latch clear of the stop screw 10 and releases the retainer 3. The retainer being tensioned

by the spring 17 thereupon moves to its open position as indicated in Figure 2, thereby freeing the bobbin-case 2 which may then be refilled. As soon as the new bobbin is inserted, the operator replaces the bobbin-case and pushes the retainer 3 back to its closed position and presses the latch 14 into the solid line position of Figure 2, behind the screw 10 so as to hold the retainer in its closed position.

It will be seen that this invention provides a simple and rugged construction for the retainer and one which is not only simple to operate but easy to adjust and which will maintain its adjustment. The arrangement of the adjusting elements so as to act in opposition to one another to limit the movement of the retainer in opposite directions makes it possible to adjust the position of the retainer very accurately. This is important in a machine of this type in order that the bobbin-case may be securely retained and positioned so as to allow free and accurate movement of the parts involved and at the same time to allow the necessary clearance between the bobbin-case and the retainer to permit the thread to pass freely therebetween during the operation of forming the stitch. The engagement of the screw 10 with the latch 14 is under sufficient pressure to frictionally retain said latch so that it is not liable to jump out during the operation of the machine. At the same time the latch is easily and quickly released when it is desired to replace the bobbin. The spring 17 holds the retainer out of the way during the operation of changing bobbins.

It is obvious that various changes may be made in details, within the scope of the appended claims, without departing from the spirit of this invention. It is, therefore, to be understood that this invention is not to be limited to the specific details shown and/or described.

Having thus described the invention what is claimed is:

1. In a device of the kind described, a support, a bobbin case removably mounted thereon, a retainer movably mounted on said support having a bobbin case engaging part, positioning means on the retainer cooperating with the support, said retainer having an arm extending substantially parallel to the bobbin case engaging part, and a latch disposed to engage the arm to position the bobbin case engaging part.

2. In a device of the kind described, a support, a bobbin case removably mounted thereon, a retainer movably mounted on said support having a bobbin case engaging part, positioning means on the retainer cooperating with the support, said retainer having an arm extending substantially parallel to the bobbin case engaging part, a latch disposed to engage the arm to position the bobbin case

engaging part, and means for urging said arm toward said latch.

In testimony whereof I affix my signature this 24th day of March, 1930.
